CLAIM

The ornamental design for a mold for ice cube as shown and described.

DESCRIPTION

FIG. 1 is a top perspective view of a mold for ice cube showing the new design;

FIG. 2 is a bottom perspective thereof;

FIG. 3 is a front view thereof; the rear view, left side view, and right side view being identical;

FIG. 4 is a top view thereof; and,

FIG. 5 is a bottom view thereof.

The surface shading is intended to depict surface contour and forms no part of the claimed design. The broken lines in the drawings form no part of the claimed design.
